UNITED STATES PATENT OFFICE.

EDWIN H. FLINT, OF CINCINNATI, OHIO.

SAFE-LOCK.

SPECIFICATION forming part of Letters Patent No. 338,505, dated March 23, 1886.

Application filed November 24, 1884. Serial No. 148,726. (Model.)

To all whom it may concern:

Be it known that I, EDWIN H. FLINT, of Cincinnati, Hamilton county, Ohio, have invented new and useful Improvements in Safe-locks, of which the following is a specification.

My invention, as to its first and principal part, relates to an improvement in those safe-locks in which protraction and retraction of the door bolt-work is effected by a screwing motion, so that, even in event of the destruction of the lock proper, such door bolt-work will remain securely locked against clandestine attempts to retract it. With this object in view the construction is further such that (except during legitimate operation of the door bolt-work) the lock-bolt and the door bolt-work are completely disconnected from each other. The said screwing action may either consist in a spiral movement of the door-bolts themselves, (or parts of them,) or 15 may be derived from rotation of nuts thereupon, as hereinafter fully explained.

My invention further comprises new and improved means for subordinating the tumbler system of a safe-lock to the timer, in which a peculiarly arranged double-headed pinion capable of being brought into gear with cog-wheels on two of the tumblers operates (for the time being) to maintain these two particular tumblers "out of gate," and (while so geared) to prevent operation of the angle-bar, and to thereby prevent opening of the lock.

In the accompanying drawings, Figure 1 is a partly-sectioned elevation of a safe-lock embodying my invention, the door-bolts and also the lock-bolt being shown retracted. Fig. 2 is a similar elevation, in which these bolts are shown protracted. Fig. 3 is a perspective view showing the device for preventing rotation of one of the door-bolt members. Fig. 4 is an elevation showing the tumbler and the timer mechanisms with their timer-connection set. Fig. 5 is a similar elevation of the same parts in the discharged condition of said connection. Figs. 6 and 7 are edge views of the tumbler mechanism respectively in the set and discharged conditions of the timer. Fig. 8 is a section on the line 8 8, Fig. 2. Figs. 9, 10, 11, and 12 illustrate modifications of my door bolt-work.

A may represent portions of the frame of a safe-lock.

B may represent portions of a safe-door, of which b represents the edge to which the hinges (not here shown) are attached. The door-bolts (now to be described) are retained in proper position by guides a a'.

Each door-bolt consists, preferably, of two members, D E, one of which (say the member D) is screw-threaded interiorly, as at d, to receive the exteriorly screw-threaded portion e of the other member. Both of said members are capable of endwise movement (protractile for locking and retractile for unlocking) within said guides. Rotation of the member, D, nearest the hinge edge of the door is prevented by any suitable means—such as a projection, d', that occupies a slot, a", in the case. The member E, on the contrary, is free to revolve (with a spiral motion about its geometrical axis) within the guides a a'. Such spiral revolution of the member E (consequent on the described screw-threaded connection of the members D and E and the prevention of rotation of one of them) operates either to lengthen or shorten the compound bolt D E as a whole, according to the direction of rotation of said member E. Such lengthening operates to thrust the outer extremities of both bolt members into the appropriate recesses or keepers of the safe-jambs, (not here shown,) from which recesses again reverse rotation of the said member E operates to free them. Such rotation is made possible (after release of the lock-bolt from the dogging mechanism of the lock proper) by the means following: Each member E has a long pinion, G, which pinions gear in idlers H H, both of which gear to a wheel, I, whose beveled portion J (when the safe-bolt reaches its protracted position) comes into mesh with a bevel-wheel, K, whose shaft L terminates outside the safe-door in a handle, M. The wheels H H and I are all journaled to head N of the lock-bolt O, whose protractile and retractile movements may be accomplished by means of the usual angle-bar, P, which (when the gates q of the entire group of tumblers Q are brought into alignment) becomes liberated for customary use in protracting the lock-bolt. Such protraction brings the beveled portion J of the wheel I into gear with its drive or

master wheel K, whose rotation to or fro operates to screw the said door-bolt members out or in, in the manner already explained. Shoulders e' on the said bolt members serve 5 to limit their play within their guides a a'.

The tumbler mechanism (except as to the hereinafter-described devices which connect it with the timer) may have the usual or any suitable form and requires no specific description.

a'' represents the usual fixed stud about which the group Q of tumblers revolve.

R represents the driving-tumbler, whose attached spur-wheel T'' gears to and derives 15 motion from the customary master-wheel T' upon the operating arbor U, which arbor communicates outside the lock with the usual dial, S, and operating-handle T.

The devices which connect the tumbler and 20 time mechanisms are as follows: The outermost tumbler, Q^v, of the group has a spur-wheel, T''. W W' is a double-headed pinion, which is pivoted at one end to the lock-case, (where its member W gears permanently with 25 the spur-wheel T''), and at its other end to a latch, X, that is connected by pivot x to the case. Attached to the latch X is a spring-bridle, Y, whose engagement at its notch y upon the trigger Z of the timer operates to 30 hold the member W' of the double-headed pinion W W' in gear with the wheel T'', and by so doing to compel synchronous rotation of the two tumblers R and Q^v, so that by setting 35 said tumblers out of gear before engagement of the pinion member W' they are retained to that condition until disengagement of the said member (by release of the timer attachment) permits the "combination" to be operated. This release is brought about by impact of 40 one or other of the customary tappets, 1 2, of the timer.

The above-described preferred form of my safe bolt-work is susceptible of various modifications; for example, my said work may 45 take the form represented in Fig. 9, in which the screw-threads d'' and e'' of my two bolt members D and E are both external and respectively of right and left spirality, and are tapped within correspondingly right and left 50 threads a^v within the guide a'. Co-rotation and simultaneous protraction and retraction of the said bolt members are secured by means of a non-circular tongue, e''', upon one bolt member fitting within a corresponding socket, 55 d''', within the other bolt member.

Another possible form of my safe bolt-work is shown in Fig. 10, wherein pinions G' are 60 separate pieces from the bolt members E and revolve in bearings F upon the case, and have 65 interior right and left screw-threads g g', for the correspondingly screw-threaded shanks d'' and e'' of the door-bolt members. In this form the spiral motion is confined to the safe-bolt adjunct G', and the motion of both bolt 65 members is simply rectilinear, their rotation

being prevented by any suitable mechanical expedient—such as pins 3, occupying channels 4 in such members.

For doors of large safes the safe-bolt motion of either of the forms above described may be 70 communicated to distant bolts E' by means of any customary or suitable transmitting mechanism—such, for example, as shown in Fig. 11, in which bolts E, operated as described in Fig. 10, are (by means of customary carrying-bars 75 5) connected rigidly to such distant bolts E', which in turn may (by customary rods, 6, angle-bars 7, and levers 8) themselves operate on such distant bolts, as shown at E'' and D'.

Still another mode of transmitting motion 80 from such safe bolt-work to distant safe-bolts is shown in Fig. 12, in which sprockets 10 (upon a bevel-wheel, J, journaled to the lock-bolt head) communicate (by chains 11) with pinions G' (similar to those represented in Fig. 85 10) upon the distant bolts E of said Fig. 12. From this form the wheels H and the cylindrical portion of the wheel I are omitted as unnecessary.

The forms shown in Figs. 9, 10, 11, and 12 90 may obviously be applied to safes which have door bolt-work only on the free edge of the door.

If desired, all or any number of the door-bolts of a safe having many bolts may be 95 adapted to operate by a screwing motion in one or other of the forms above described.

I claim as new and of my invention—

1. In a safe-lock, the combination, with the lock-frame, of a two-part door-bolt having 100 screw-threaded connection between said parts, a pinion secured to one member of said bolt, the knob or handle outside the safe-door, and geared connection between said handle and pinion, substantially as and for the purpose 105 set forth.

2. In a safe-lock, the combination, with the lock-frame, of a two-part door-bolt having screw-threaded connection between said parts, a stop for preventing the rotation of one section, and a pinion secured to the other section of said bolt, the knob or handle outside the safe-door, and the geared connection between 110 said knob and pinion.

3. In a safe-lock, the combination, with the 115 lock-frame A, having the guides a a', of the two-part lock-bolt D E, having screw-threaded connections d e and the shoulders e', the stop for preventing the rotation of the section D, the pinion G on the section E, the handle M, 120 and the geared connection between said handle and pinion G, substantially as and for the purposes set forth.

4. In a safe-lock, the combination, with a 125 two-part door-bolt having screw-threaded connection and an elongated pinion on one member of said bolt, of the lock-bolt, the bolt-operating handle or knob on the outside of the door, its shaft passing through the door, a pinion secured to the inner end of said shaft, 130

and gear-wheels carried by the lock-bolt for connecting said pinion with said elongated pinion, substantially as set forth.

5. The combination, with a screw-actuated door-bolt and its operating knob or handle having a shaft extending through the door and a master-wheel secured thereto, of the lock-bolt and the gear-wheels carried by said lock-bolt, for connecting said master-wheel and bolt 10 when said lock-bolt is protracted, as set forth.

6. The combination, with the lock-frame and a pair of screw-actuated door bolts having pinions G G, and the operating knob or handle M, having shaft L and master-wheel 15 K, of the lock-bolt O, having the cross-head N and the gear-wheels carried by said cross-head, for connecting the pinions G G and master-wheel K when the lock-bolt O is protracted, substantially as set forth.

20 7. In a permutation-lock, the combination, with the tumblers having spurs or teeth and a pinion gearing therewith, for compelling their synchronous rotation, of the time mechanism and connecting mechanism between said time

mechanism and pinion, for moving the latter 25 in and out of engagement with said spurs or teeth, for the purpose set forth.

8. The combination, with the tumblers Q^{IV} and R, having the spur-wheels T'' and T'', respectively, of the double-headed pinion W' 30 W, gearing with said spur-wheels, the latch X, in which one end of the shaft of said double-headed pinion is journaled, and the time mechanism for controlling the position of said latch, substantially as set forth. 35

9. The combination, with the tumblers Q^{IV} and R, having spur-wheels T''' and T'', respectively, of the double-headed pinion W' W, the latch X, the spring-bridle Y y, the trigger Z, and the time mechanism, substantially as and 40 for the purposes set forth.

In testimony of which invention I hereunto set my hand.

EDWIN H. FLINT.
